VOLTAGE REGULATOR.

Application filed August 8, 1923. Serial No. 656,334.

This invention relates to regulators for generators designed to correspondingly vary the speed of the generator with the variations in the load to maintain an approximately constant voltage and one of the objects of the invention is to accomplish such voltage regulation by the combined influence of a throttle controlling means and a field resistance controlling means without the spring adjustments of the former affecting the operation of the latter.

While the invention is not confined to any particular adaptation, it is especially applicable to internal combustion engine driven farm lighting and power plants and serves to approximately proportion the fuel consumption to the actual load.

The present invention constitutes an improvement on, or a development of, the invention covered by my United States patent for generator regulators No. 1,434,365, issued November 7, 1922, and my United States patent for regulators for generators, No. 1,472,788, issued November 6, 1923, and provides the latter with independent field resistance regulating means whereby the spring adjustments for the throttle control may be accomplished without affecting the operation of the field resistance regulating means, thus more effectively avoiding the development of excessive voltage upon the sudden change from full load to minimum load conditions.

With this end in view the present invention provides in addition to the regulating means for varying the speed of the generator with the load, a separate and independent automatically operated switch for introducing resistance in series with the shunt field when a predetermined voltage is attained.

Instead of regulating the voltage by maintaining a constant generator speed, a series field winding is used to buck or oppose the shunt field winding and thereby weaken the field strength as the load increases, while automatic means simultaneously opens the throttle of the engine to increase its speed. These two influences are so related that they maintain the voltage approximately constant, but at times when the reduction in speed of the generator lags behind the reduction in load, a voltage coil sensitive to an abnormal increase in voltage and independent of the automatic throttle-operating means is now employed to operate a switch

for weakening the shunt field of the generator by introducing resistance in series therewith and thus avoid the development of an excessive voltage.

With the above and other objects in view the invention consists in the voltage regulator as herein claimed and all equivalents.

Referring to the accompanying drawing, the figure constitutes a diagram of a voltage regulator for generators constructed in accordance with this invention.

In the drawing 10 indicates a generator driven by an internal combustion engine, the throttle valve 11 of which is controlled by a solenoid having windings connected with the generator windings, as will be described. The generator as shown is of the shunt type and supplies the mains 12 containing lamps 13 or other translating devices. The shunt field winding 14 of the generator is opposed by a bucking series field winding 15 which becomes stronger as the load on the mains increases and thereby opposes a greater influence to the shunt field to weaken the field strength. At the same time a series coil 16, also in the load circuit and strengthened by the increasing load, opposes to a greater extent the influence of a shunt of voltage coil 17 to effect a further opening movement of the throttle valve of the engine to increase the speed of the engine.

The solenoid is so constructed that the voltage coil 17 of many turns of fine wire connected in parallel with the shunt field 14 and the current or series coil 16 of few turns of large wire in the load circuit together act upon the core 21 but in opposition to each other. The solenoid core is pivotally connected to the shorter arm of a bell crank lever 23, the other arm of which is connected by a link 27 with the throttle 11 so that in the extreme upper position of the core, as when the generator is not operating and the coils are therefore not energized the throttle is held in a partly closed position, as shown. The core is held in this position by an adjustable coil spring 25 which affords a yielding resistance to the operation of the solenoid core, the adjustments of which determine the regulation.

When the generator is started with a minimum load or no load on the service mains, the series coil 16 opposes the voltage coil 17 only slightly or not at all, and the core will be drawn to a lower position against

the action of spring 25 and will move the throttle to a position practically closing the intake manifold of the engine, so that the engine operates at a minimum speed under 5 which the generator develops the line voltage. As the load increases the generator field is weakened by the bucking series field 15, as above mentioned, and the influence of the bucking current coil or series coil 16 be- 10 comes greater, tending to neutralize the influence of the voltage coil 17 and permitting the spring 25 to lift the core and move the throttle toward its open position, thus in- 15 creasing the supply of fuel to the engine to increase its speed corresponding with the in- 20 crease in the load.

The full open position of the throttle 11 is attained under the condition of maximum load and should, for any reason, the current 20 strength be increased beyond this, as upon the occurrence of an overload, the further movement of the throttle beyond its open position resulting therefrom will tend to slow down the engine. Also, with auto- 25 matic starting control, the partially closed position of the throttle for starting prevents the engine from racing before connecting the generator with the load, as is done when it is started with the throttle in full open posi- 30 tion.

The proportioning of the field windings of the generator and of the coils of the sole- 35 noid and of the throttle and its operating means is made to compensate for a change in load by causing a change in speed without a material change in voltage developed by the generator. The weakening of the generator field by the bucking coil 15 serves to facilitate the increasing of the speed of the 40 engine caused at the same time by the buck- ing influence of the series coil 16 of the dif- ferential solenoid opening the throttle, and this bucking field winding exaggerates the 45 speed variation characteristic of the genera- tor for constant voltage conditions so that the desired object is accomplished of ma- terially reducing fuel consumption to cor- 50 respond with a reduction of load.

As so far described the present invention 55 is like that covered by my Patent 1,434,365 referred to and for the increased independent regulation a resistance 30 is connected in series with the shunt field winding 14 of the generator and wires 31 and 32 connect 60 the ends of this resistance with switch contacts 33 and 34 respectively of a resistance short circuiting switch operated by a sole- noid 50 which is connected across the termi- 65 nals of the generator preferably with a resistance 51 in series therewith. Thus the field regulating resistance short circuit is controlled by a switch independent of the throttle controlling solenoid but sensitive to the variation in voltage developed by the 70 generator. Being independent it is not

affected by the spring adjustments of the solenoid core that are made for the purpose of controlling the operation of the throttle.

By means of this improvement the momen- 70 tary rise in voltage when the load is sud- denly reduced from full load to minimum load is prevented, the sudden weakening of the bucking current coil 16 accompanied by a slight strengthening of the voltage coil 17 being sufficient to cause the core 21 to move 75 to the position for closing the throttle. At the same time the voltage coil 50, because of such momentary rise in voltage, opens the contacts 33 and 34, thus breaking the short circuit around the regulating resistance 30 and including this resistance in the shunt field winding to weaken the fields and check the rise in voltage. Such tendency to abnor- 80 mal voltage is only momentary and as soon as the speed of the generator has reduced 85 to correspond with the new throttle position, the normal conditions are restored, the throttle position being determined by the solenoid 16-17 and the field resistance short circuiting switch being permitted to close by 90 the voltage coil 50.
